CLAIM

The ornamental design for a deflector plate for the
underbody of a sports car, as shown.

DESCRIPTION

FIG. 1 is a front elevation view of a deflector plate for
the underbody of a sports car showing my new design;
FIG. 2 is a rear elevation view thereof;
FIG. 3 is a side elevation view thereof; and
FIG. 4 is a top plan view thereof.

FIG.4

FIG.2

FIG.1
